UNITED STATES PATENT OFFICE.

JAMES BOWEN, OF SWANSEA, WALES.

COOLING DEVICE FOR AIR-COOLED ENGINES.

1,424,234.

Specification of Letters Patent. Patented Aug. 1, 1922.

Application filed October 18, 1920. Serial No. 417,820.

To all whom it may concern:

Be it known that I, JAMES BOWEN, a subject of the King of Great Britain and Ireland, and a resident of Swansea, county 5 of Glamorgan, South Wales, have invented a certain new and useful Improvement in Cooling Devices for Air-Cooled Engines, of which the following is a specification.

This invention relates to cooling devices 10 for air cooled engines, and in accordance therewith a device is provided comprising an air chamber fitted upon the top of the cylinder around the top fin, suitably perforated to permit of the passage of air from the 15 atmosphere thereto, and from which chamber the air is drawn through an outlet connected by piping to an ejector fitted at the end of the exhaust pipe, the exhaust gases passing through the nozzle of the 20 ejector at a high velocity, serving to draw the air from the cooling chamber and eject same to the atmosphere; a fresh supply of air rushes into said chamber through the perforations, and a continuous flow of cool 25 air thus passes over and around the cylinder head.

And in order that said invention may be 30 fully understood, it will now be described with reference to the accompanying drawings, and figures and letters of reference marked thereon.

Figure 1 is a diagrammatic view in elevation, showing the device applied to an 35 internal combustion engine.

Figure 2, to an enlarged scale, is a plan of the air-cooling chamber constructed in accordance with this invention.

Figure 3 is a side elevation of same.

Figure 4 is a side elevation of an ejector 40 adapted to be connected to the exhaust and to a pipe communicating with the cooling chamber; and,

Figure 5 shows, in sectional side elevation, another form of ejector applicable to 45 the cooling device of this invention.

Figure 6 is an end section of same.

Figure 7 is a plan of a copper conductor placed on the cylinder head for absorbing 50 heat therefrom and localizing same to facilitate the action of the device.

In carrying the present invention into effect, a cooler or air chamber *a*, consisting of an aluminium hollow body, made in one, two or three parts, (in the drawings—see 55 particularly Figures 2 and 3—it is shown as

in three sections 1^a, 2^a, 3^a) to suit the design of the engine to which it is to be fitted, is attached to the cylinder head over and around the top fin *b*, Figure 1.

Said hollow body is perforated as at *b* 60 and *c*—Figures 2 and 3, to permit air to enter same and an outlet *d* is provided to which is attached a tube or pipe *e* which may be flexible or rigid, and which is, at its other end, connected to an ejector *f* fixed 65 over the end of the engine exhaust pipe *g* which ejector is formed with a socket or union *h* for its reception. The ejector comprises (in one form) a hollow chamber formed with a nozzle *f'*, into which a jet *i*, 70 into which the end of the exhaust pipe *g* opens, projects and through which the exhaust gases from the engine are ejected at a high velocity, drawing with them air from the cooler *a* through the pipe *e*, and the 75 space around said jet in the hollow chamber of the ejector aforesaid. A fresh supply of air rushes in through the perforations *b* and *c* in the body of cooler *a* at every exhaust stroke of the engine, hence a constant flow 80 of cool air is maintained over the cylinder end.

An advantageous form of ejector *f* is shown separately in Figures 5 and 6, wherein said ejector takes the shape of a flattened 85 casing having its sides tapering from near the inlet end *A* to the outlet *B*—see particularly Figure 6—in such manner that the nozzle outlet is in the form of an elongated slot *f'*. The jet portion *i* through which 90 the exhaust gases pass from the engine is similarly tapered at its sides *j*—Figure 5—and has its ends *j'*—Figure 6—opening out fanwise from the exhaust inlet to the outlet, which latter is also in the form of an elongated slot.

At its inlet end, the ejector *f* is formed or fitted with sockets or unions *h* and *k* for connection with the pipe or tubing *e* leading from the cooling body *a*, and with the 100 exhaust pipe *g* of engine respectively. Said sockets or unions may be formed integral with the ejector end, or be affixed thereto; or said ejector inlet end may be formed open and have a detachable cover fitted thereto 105 which may have the sockets or unions aforesaid integral therewith or affixed thereto.

In Figure 7 is illustrated a baffle plate of copper placed over the cylinder head and used in combination with the air chamber as 110

a ready absorber of the heat from the cylinder head, which is thereby concentrated for action thereupon by the flow of cool air through the device. *l* and *m* are respectively 5 ribs and projections formed on and in said plate which act as guides for the air.

I claim:—

1. A cooling device for air cooled engines, comprising a perforated air chamber adapted to be fitted over the cylinder end around the top fin, means consisting of an ejector fitted on the end of the exhaust pipe of the engine, and connected to said air chamber by suitable piping, all in such manner that air is drawn from the air chamber at each exhaust stroke of the engine and is replaced by fresh air entering through the perforations in said air chamber, and a constant current of cool air is caused to flow over the cylinder end while the engine is working.

2. In a cooling device for air-cooled engines, including in combination with the cylinder and the exhaust pipe for the engine as claimed in claim 1, an air chamber comprising a flat plate formed with downwardly curved edges and suitably perforated for the passage of air thereinto, adapted to fit over the top of the cylinder, around the top fin, and formed with an outlet or socket, a tube connecting with the socket of the air chamber, and an ejector fitted on the end of the engine exhaust pipe and communicating with the end of the tube opposite its connection with the air chamber for the purpose of drawing air through the tube from said chamber. 25 30 35

In testimony whereof I have affixed my signature hereto this 23rd day of September 1920.

JAMES BOWEN.
